CLOSURE PLUG WRENCH

Frank J. Tomsek, Detroit, Mich.

Application March 18, 1943, Serial No. 479,647

1 Claim.

(Cl. 81—71)

My invention relates to the application and removal of threaded caps and plugs of the type employed in oil drums and the like, and has among its objects and advantages the provision of an improved plug tool designed to facilitate turning of such closures, wherein the device is so designed as to be applicable to a large range of sizes and shapes.

In the accompanying drawings:

Figure 1 is a side view of one part of the tool.

Figure 2 is a view taken from the position indicated by line 2—2 of Figure 1.

Figure 3 is a fragmentary view of the tool part illustrating the same applied to a screw cap.

Figure 4 is a sectional view taken along the line 4—4 of Figure 3.

Figure 5 is an enlarged sectional view of a screw plug illustrating the manner in which a metallic cap may be ruptured with one end of the tool part of Figure 1.

Figure 6 is an end view of a different form of screw plug illustrating a second tool part employed in conjunction with the art of Figure 1.

Figure 7 is a side view illustrating the assembled relationship between the tool parts of Figures 1 and 6.

Figure 8 is a side view of the tool part of Figure 6.

Figure 9 is an end view of the tool part of Figure 8.

Figure 10 is a view of the opposite end.

Figure 11 is a view illustrating the application of the tool part of Figure 8 to one type of screw plug.

Figure 12 is a similar view in connection with another form of screw plug.

Figure 13 illustrates the tool part of Figure 8 in conjunction with another type of screw plug.

Figure 14 illustrates the tool part applied to a further modified form of screw plug.

Figure 15 illustrates its application to another type of screw plug, and

Figure 16 is a sectional view along the line 16—16 of Figure 15.

In the embodiment of the invention selected for illustration, Figure 1 illustrates a tool part 10 comprising a rod or handle 12 having a cold chisel formation 14 at one end. The opposite end of the handle 12 is slightly rounded as at 16 to provide a striking face. A right angular wrench member 18 is welded to the handle 12 a short distance inwardly from the striking face 16. This wrench is provided with a slot 20 in its end so arranged as to provide two spaced and similarly shaped fingers 22. The slot 20 is extended a

short distance up the sides of the wrench member 18, as at 24.

Figures 3 and 4 illustrate the application of the wrench member 18 to a screw cap or plug 26 threaded into the neck 28 on the end wall 30 of a drum 32. Such end walls are usually placed a slight distance inwardly from the end of the drum. The plug 26 includes a depression or socket formation 34 in its outer end, with two lugs 36 projecting inwardly from the side wall of the depression. In a plug construction of this type, the fingers 22 are receivable in the depression 34, and the slot 20 is sufficiently wide to provide ample clearance for the lugs 36, thus the fingers 22 take positions on opposite sides of the lugs 36 to constitute abutments for engagement with the fingers when the tool is rotated about the axis of the wrench member 18 through the application of turning forces on the handle 12. The wrench member 18 is of sufficient length to provide clearance for the handle 12, as when the tool is used in connection with drum structures of the type illustrated in Figure 3.

Figure 5 illustrates a screw plug 38 threaded into the drum neck 40. This plug is covered by a metal cap 42. In such constructions, the cap 42 may be ruptured by the cold chisel formation 14 to provide entrance for the wrench member 18.

Figures 8, 9 and 10 illustrate a second tool part 44, wherein a flat and generally rectangular metallic body 46 is provided with a bore 48 for the reception of the handle 12, as in Figure 7. The body 46 may be fixedly related to the handle 12 by a set screw 50 having its head 52 lying flush with the bottom face 54 of a recess 56 in one side edge of the bottom.

One end of the body 46 is provided with a recess 58 spaced to provide two fingers 60. The other end of the body 46 is provided with angular faces 62 onto opposite side edges. The faces 62 are arranged at angles of 45 degrees with respect to the side faces 64 of the body 46, and the faces on the opposite sides of the body converge slightly in the direction of each other to provide a tapered wrench end 66 of six sided contour.

Figure 11 illustrates one of the fingers 60 inserted in a square depression 68 in a screw cap or plug 70. Thus the finger 60 functions as a wrench element for coaction with a plug structure of the type shown. In Figure 12, the screw plug 72 is provided with a square nut formation 74, this formation being receivable in the slot 58 so that the fingers 60 may secure a grip on the nut formation. Screw plugs of the type illus-

trated in Figures 11 and 12 are usually provided with hexagonally shaped flanges 16.

In Figure 13, the screw cap or plug 78 is of the depressed type and is provided with a transverse web 80. This web is receivable in the slot 58 to engage the fingers 60. In Figure 14, the screw cap or plug 82 includes a large nut formation 84, which formation is receivable in the slot 56, so that the body 46 may have a grip on the nut formation when the former is turned relatively to the latter.

In Figures 15 and 16, the screw cap or plug 86 is provided with a large depression 88 of square contour. The wrench formation 66 fits diagonally in the depression 88, as in Figure 16, whereby a wrench connection may be established between the formation 66 and the plug 86 through rotation of the body 46.

Figure 6 illustrates a construction wherein the screw cap or plug 90 includes an annular depression 92 and two inwardly extending lugs 94. The fingers 60 are adapted to engage the lugs 94 to function as a wrench.

Good leverage for the body 46 is attained through the medium of the tool part 12.

The tool structure is so designed as to operate successfully on a large range of sizes and shapes. Considerable difficulty has been experienced in removing closure plugs in drum structures. It

is common practice to employ a hammer and a cold chisel for loosening the plugs. These plugs are usually so located as to make it difficult to apply ordinary wrenches. Cold chisels cut and mar the closure plugs, and many accidents have been caused through the use of hammers and cold chisels. In the instant case, the tool is easily and quickly applied and operates efficiently in the removal of various types of closures.

Without further elaboration, the foregoing will so fully explain my invention, that others may, by applying current knowledge, readily adapt the same for use under various conditions of service.

I claim:

15 In a wrench of the type described, an elongated cylindrical body bar having an arm projecting transversely therefrom adjacent one end, a flat elongated bar having a circular opening medially of its ends slidably mounted in transverse arrangement on the body bar and provided with a recess in its side adjacent the opening, a set screw at the bottom of the recess to engage the body bar to fix the flat bar thereon, and a flattened head portion formed at one end of the flat bar and tapering outwardly and having V-shaped end portions at each end thereof, the base of the head being of less width than the width of the flat bar to form shoulders.

FRANK J. TOMSEK.
